Francis H. Webster

UNITED STATES PATENT OFFICE.

FRANCIS H. WEBSTER, OF ST. LOUIS, MISSOURI.

EMBROIDERY NEEDLE.

1,407,609.

Specification of Letters Patent. Patented Feb. 21, 1922.

Application filed November 4, 1921. Serial No. 512,700.

To all whom it may concern:

Be it known that I, FRANCIS H. WEBSTER, a citizen of the United States, and resident of St. Louis, Mo., have invented certain new and useful Improvements in an Embroidery Needle, of which the following is a specification.

This invention relates to improvements in an embroidery needle, the same consisting of a hollow handle, an adjustable gauge, a detachable needle and a means for holding the gauge and needle in a set position within the handle.

The object is to construct a neat, simple, cheap and unique device for embroidery purposes, the same being so arranged as to permit any size of needle to be inserted and easily adjusted and clamped in the handle, and a guard likewise adjusted in the handle and over the needle to regulate the distance the needle is to be passed through the material, which likewise regulates the loop of the thread or yarn to be formed on the opposite side of the material, through which the needle is passed.

Figure 1, is a perspective view of my complete invention.

Fig. 2, is a detail perspective view of one of the needles made use of.

Fig. 3, is a detail perspective view of the gauge.

Fig. 4, is a side view of my invention.

Fig. 5, is a bottom plan view of the same.

Fig. 6, is a central sectional view of the same.

Fig. 7, is an enlarged cross-sectional view taken on the line 7-7 of Fig. 6.

Fig. 8, is a perspective view of the needle showing a modified form of supporting shank.

In the general construction of my invention I provide a handle 9, the same being of tubular construction and on the base is provided a clamp 10, which is in any manner fastened thereto. In the member 9 is provided a hole 11 through which is placed a tightening screw 12, said screw being provided with a knurled head 13, by which the screw can be operated. Adjacent to this hole I provide a second hole 14 and through this hole is passed the thread or yarn which is in turn fed to the point of the needle. In the hollow handle and inserted through the free open end 15 is placed a gauge 16, this is constructed of a strip of material comprising an elongated flat section 17, and an

up-turned end 18, the same being provided with an elongated slot 19, through this slot is placed the screw 12, this gauge is supported on an internally screw-threaded nut 20 of such size as to prevent the same from turning when the screw is adjusted.

On the top of the gauge and between it and the upper inner surface of the handle is inserted the needle 21, and said needle is supported in position between the gauge and the handle by means of its shank 22 which is provided with a slot 23, which passes over the screw 12 and it is also provided with a hole 24, which corresponds and registers with the hole 14 of the handle. The blade 25 of the needle is passed through the slot of the gauge but under the up-turned end 18. This up-turned end acts as a limit for the insertion of the needle through the goods.

The shank of the needle is constructed to have two vertical walls 26, terminating into horizontal flanges 27, by this structure considerable tension may be put on the screw thereby firmly clamping the needle in position between the gauge and the handle, at the same time supporting the gauge and preventing the handle from spreading, owing to the fact that its edge 28 is unfastened.

I may, if desired, construct a needle of a shank as that indicated by the numeral 29, Fig. 8, in this instance the shank is semi-circular in form instead of a rectangular structure as that shown in Fig. 2.

When a needle is inserted in position and then clamped in the handle the thread or yarn is passed through the opening 14, and then through the eye of the needle as shown by dotted lines in Fig. 6.

The device is constructed with an assortment of needles of various lengths and widths which are used for various purposes and for different material, and when any one of the assortment of needles is to be used, the thumb-nut is loosened, the needle is removed from its clamped position and another needle is inserted in its place and by tightening the screw the same is held in rigid position in the handle.

Having fully described my invention what I claim is:

1. A needle of the character described comprising a handle, a clamping screw supported thereby, an adjustable gauge supported by the clamping screw, a needle having a supporting shank which is inserted in

the handle and slipped over the clamping screw, a thread supporting eye formed in the handle and in the needle through which the thread is passed, substantially as specified.

2. A needle of the character described comprising a handle, a gauge, a detachable needle, a clamping screw supported by the handle and passing through the base of the 10 needle and the gauge, and a nut provided on

the screw for clamping the needle and gauge in position in the handle, substantially as specified.

In testimony whereof, I have signed my name to this specification, in presence of two subscribing witnesses.

FRANCIS H. WEBSTER.
